UNITED STATES PATENT OFFICE.

THOMAS O'MALLEY, OF MCKEESPORT, PENNSYLVANIA.

TRUSS.

No. 820,728.

Specification of Letters Patent.

Patented May 15, 1906.

Application filed November 14, 1905. Serial No. 287,381.

To all whom it may concern:

Be it known that I, THOMAS O'MALLEY, a citizen of the United States of America, residing at McKeesport, in the county of Allegheny and State of Pennsylvania, have invented certain new and useful Improvements in Trusses, of which the following is a specification, reference being had therein to the accompanying drawings.

10 This invention relates to certain new and useful improvements in trusses; and the invention has for its primary object to provide a novel form of truss which can be easily and quickly secured to the body to exert a pressure upon a rupture or the like injury.

Another object of my invention is to provide a truss that can be adjusted to different parts of the body and firmly held in position to accomplish the desired results.

20 The invention consists in the novel construction, combination, and arrangement of parts hereinafter described and claimed.

Referring to the drawings accompanying this application, like numerals of reference 25 designate corresponding parts throughout the several views, in which—

Figure 1 is a side elevation of one end of my improved truss. Fig. 2 is a top plan view of the same. Fig. 3 is a vertical sectional view 30 taken on the line $x-x$ of Fig. 2. Fig. 4 is a plan of a swiveled buckle used in connection with the truss. Fig. 5 is a plan of a spring-carrying plate, and Fig. 6 is a fragmentary view of a body equipped with my improved 35 truss.

To put my invention into practice, I construct my improved truss of a piece of fabric belting 1, to one end of which is secured a conventional form of buckle 2, said buckle being 40 adapted to receive the opposite end of the belting. Adjacent to the buckle end of the belting I mount an annular plate or buckle 3, which is held in engagement with the belting by a metallic cleat 4, the ends of which are 45 bent upwardly, as at 5 5, to engage the plate 3. The plate is further held in engagement with the fabric by a vertically-disposed rivet 6, which passes upwardly through the fabric belting centrally of the plate, and said rivet

retains a strap 7 upon the bottom of the cleat 50 4, the object of which will be presently described.

Upon the plate 3 is mounted a coiled spring 8, the end of said spring being secured to the plate by straps 9 9, which are riveted to the 55 plate, as at 10 10. The ends of the strap are bent beneath the plate 3, as at 11 11, to insure a positive engagement of the spring with said plate. To the opposite end of the spring is secured a pad or cushion 12, which is adapted 60 to bear against the body to be treated or sustained by the truss.

Slidably mounted upon the fabric belting 1 is a strap 14, the end of which is adapted to be held by a buckle 15, carried by a strap 16, 65 swiveled in the strap 7 upon the underneath face of the belting 1. The buckle 15 is swiveled, whereby it can be swung from one side of the fabric belting to the other, according to the position in which the belting is placed 70 upon a body.

In Fig. 6 of the drawings I have illustrated the application of my improved truss to a body, and by referring to said figure it will be observed that the truss surrounds the body 75 and that the cushion or pad 12 bears against one part thereof. To prevent the truss from turning or becoming displaced, the strap 14 passes between the limbs of the body and has its ends secured to the buckle 15. I do not 80 care to confine myself to the manner in which I have secured the spring to the plate 3 or to the character of buffer used in connection with the truss, and such changes in the construction of my improved truss as are permissible by the appended claims may be resorted to without departing from the spirit and scope of the invention.

What I claim, and desire to secure by Letters Patent, is—

1. A truss embodying a fabric belt adapted to have its ends secured together, a metallic plate carried by said belt, a rivet passing through said plate and said belt, a spring mounted upon said plate, a pad carried by 95 said spring, a strap having one end adjustably mounted upon said belt and adapted to have its other end detachably secured to said

belt, adjacent said plate, substantially as described.

2. In a truss, the combination with a belt, of a plate mounted thereon, a cleat extending across said belt on the opposite side to the plate, said cleat having its ends bent around the edge of the plate, straps riveted to said plate, a spring having one end arranged be-

tween said plate and said straps, and a pad carried by the opposite end of said spring. ¹⁰

In testimony whereof I affix my signature in the presence of two witnesses.
